ATTORNEY

UNITED STATES PATENT OFFICE.

HARRY THAYER KINGSBURY, OF KEENE, NEW HAMPSHIRE.

DESIGN FOR A TOY-CAR BOTTOM PLATE.

SPECIFICATION forming part of Design No. 31,101, dated June 27, 1899.

Application filed May 31, 1899. Serial No. 718,915. Term of patent 14 years.

To all whom it may concern:

Be it known that I, HARRY THAYER KINGSBURY, a citizen of the United States, residing at Keene, in the county of Cheshire, State of New Hampshire, have invented a certain new and original Design for a Toy-Car Bottom Plate, of which the following is a description, reference being had to the accompanying drawing and to the letters of reference marked ⁵ thereon.

This invention relates to a new and original design for a toy-car bottom plate; and the leading feature of the design consists of the toy-car bottom plate of the shape and configuration hereinafter described, and illustrated ¹⁵ in the accompanying drawing, in which the figure is a plan view of a bottom plate embodying my design.

In the drawing the main portion of the bottom plate is shown as a flat piece A, having ²⁰ its side edges from a to b generally curved

contour interrupted by slight depressions c c d d and projecting perforated ears or loops e, the corners at a a b b being rounded off. The opposite ends of the plate from a to a and b ²⁵ to b are shown as having projecting ears or loops f, while the plate A at each end and in the middle adjacent each edge is provided with slots g.

The essential feature of the design is the ³⁰ bottom plate with the projecting side ears or loops and adjacent depressions c d.

I claim—

The design for a toy-car bottom plate, substantially as shown and described. ³⁵

In testimony whereof I affix my signature in presence of two witnesses.

HARRY THAYER KINGSBURY.
